TYPE-WRITER APPLIANCE.

1,116,076.

Specification of Letters Patent.

Patented Nov. 8, 1914.

Application filed February 10, 1914. Serial No. 817,792.

To all whom it may concern:

Be it known that we, ERNEST E. KASER, WALTER V. HUMBLE, and EMILE G. REMMERS, citizens of the United States, and residents of Oklahoma city, in the county of Oklahoma and State of Oklahoma, have made certain new and useful Improvements in Type-Writer Appliances, of which the following is a specification.

10 Our invention is an improvement in type-writer appliances, and has for its object to provide an appliance for use with type-writing machines, for permitting the paper in continuous strips to be used in the type-writer, thereby economizing in time, by eliminating the necessity of removing and replacing separate sheets of paper, and wherein mechanism is provided for supporting rolls of paper suitable for fair and carbon copies, and a roll of carbon or impression paper, and for conducting the said strips in superposed relation beneath the platen roll of the typewriter, and for severing the strips of paper transversely into 25 sheets of suitable size, after they have been written upon.

In the drawings: Figure 1 is a longitudinal vertical section of the improved appliance, Fig. 2 is a top plan view, Fig. 3 is a partial side view, Fig. 4 is a longitudinal section of the carbon strip receiving roll, Fig. 5 is a section on the line 5—5 of Fig. 4 looking in the direction of the arrow, Fig. 6 is a view from the inner side of the end 35 plate or head of the casing shown in Fig. 4 in connection with the carbon receiving roll, and, Fig. 7 is an edge view of the locking disk for the spring.

The present embodiment of the invention 40 is shown in connection with the carriage 1 of a typewriter 2, the said carriage being mounted to slide on balls 3, and carrying the platen roll 4. A frame consisting of cheek plates 5 and connecting rods 6 is connected 45 with the carriage 1, the said cheek plates having at their rear ends depending arms 7, each of which has a bearing 8 for engaging the rear bar 9 of the carriage, and a set screw 10 is threaded through each bearing 50 into contact with the said bar 9.

The front end of each of the cheek plates is provided with a lateral outwardly extending split lug 11, which engages the end rail of the carriage; and a set screw 12 is pro-

vided for clamping the split lug on the carriage. Paper carrying rolls 13 and 14 are journaled in the cheek plates, in parallelism with each other and with the platen roll, and a carbon carrying roll 15 is journaled parallel with the said rolls between the 55 same.

The paper rolls 13 and 14 are provided with roughened knobs 16 outside one of the cheek plates, for convenience in turning the said rolls, and the said rolls are supported 65 in open bearings in the upper edges of the cheek plates, as shown in Fig. 2. The roll 15 is also provided with a knob 17 outside of one of the cheek plates, and each of the rolls is provided with a housing to be described. Strips of paper 18 and 19 are mounted on the rolls 13 and 14, the strip 18 being suitable for a fair or original copy, and the strip 19 being carbon or duplicate 70 copy.

A housing 20 is arranged on the roll 13, the said housing being of approximately cylindrical shape and having an opening 21 at its under side for permitting the passage of the strip 18 to the platen roll. The ends 75 22 of the housing have hubs or bosses 23 fitting the shaft of the roll 13, as shown more particularly in Figs. 1 and 2. A similar housing 24 is arranged on the roll 14, the ends of the said housing having hubs or 80 bosses 25 for engaging the shaft of the roll. The housing is also provided with a longitudinally extending slot or opening 26 on its under face for permitting the passage of the strip 19 from the housing. 85

A housing 27 is arranged on the roll 15, the said housing having the slot or opening 28 on its under surface, and having hubs 29 for engaging the shaft of the roll at the ends thereof. The outer end of each of 95 the hubs 23, 25 and 29 is adjacent to the inner face of the adjacent cheek plate to prevent longitudinal movement of the housing.

A strip 30 of carbon or other suitable impression paper has one of its ends winding 100 on the roll 15, and the other end of the said strip winds upon a roll 31 journaled in open bearings in the cheek plates 5, and having a housing 32 similar to the housing 27. The said housing 32 has a longitudinal 105 slot or opening 33 on its under side, for permitting the passage of the strip 30 to the roll. The strips 18, 19 and 30 pass from the

several rolls over a rod 34, journaled in bearing lugs 35 extending rearwardly from the front portion of the cheek plates, and an angle plate 36-37 is supported by the said rod 34.

The portion 36 of the plate extends approximately vertical, behind the platen roll 4, and the portion 37 extends rearwardly and upwardly as shown, to form a support 10 for the strip 18, in case there should be some slack in the said strip. The portion 36 of the angle plate forms a support for the three strips as they pass beneath the platen roll, and a guide plate 38 is arranged at the 15 front of the platen roll, the said guide plate being connected to the cheek plates, as indicated at 39. The plate 38 forms a guide for the strips, as they leave the platen roll, and the said strips after leaving the platen roll 20 pass upwardly, as shown, the strips 18 and 19 passing through a cutting device, arranged to cut the said strips transversely, while the strip 30 passes to the roll 31 and winds thereon.

25 The cutting devices comprise a pair of end plates 40 connected by cross pieces 41, each of which has a fixed blade 42 at the upper edge thereof, the upper faces of the said blades 42 being flush with the upper 30 edges of the plates 40. The plates 40 are further connected by means of cross bars 43, the said bars forming guides or rests for the movable blades to be presently described. Each of the plates 40 is provided at its rear 35 end with an upward extension 44, and a shaft 45 is journaled in the extensions, the ends of the shaft extending through slots 46 in the cheek plates 5. At one end the said shaft 45 is provided with a crank arm 40 47, the said arm extending forwardly toward the front of the frame, and having a finger piece 48 at its free end for convenience in operating the said arm.

The shaft 45 is provided near each end 45 with a radial arm 49, each arm having a slot 50 at its free end, and a link 51 is connected with each arm, each link having a pin 52 for engaging the slot 50 of the arm. Movable blades 53 are secured to the links 50, the said blades 53 normally seating on the bars 43, and the said blades are secured to the links 51, by means of screws 54. Each of the blades 53 is beveled at its rear edge from above downwardly, and rearwardly, 55 and the fixed blades 42 are beveled in the same direction, as shown more particularly in Fig. 1.

The bars 43 and the blades 53 when at rest are spaced apart from the blades 42, to permit the passage of the strips 18 and 19, and the said blades 53 are moved simultaneously rearwardly, to sever the strips 18 and 19 by means of the crank arm 47. It will be evident that when the shaft 45 is oscillated the movable blades will be moved rear-

wardly, and the strips 18 and 19 will be sheared transversely between the fixed and the movable blades.

The blade supporting carriage comprising the links 51 is returned to original position after cutting the strips, by means of coil springs 55, the said springs being arranged at the ends of the carriage, and each spring being connected to an eye 56 on the adjacent link at one end, and an upwardly 70 extending perforated lug 57 at the front end of the adjacent plate 40 at the other end.

The cutting device is supported by means of threaded stems 40^a, extending laterally outward from approximately the center of 80 each of the plates 40, and passing through vertical slots 46^a in the cheek plates 5. Each stem 40^a is engaged by a head or nut 41^a outside the cheek plate, and by means of the nuts or heads, the plates 40 may be 85 clamped against the adjacent cheek plates, to hold the cutting device in adjusted position.

The receiving roll 31 for the carbon strip 90 is provided with a longitudinally extending 90 series of radial teeth or spurs 58 for engaging the end of the strip to hold the strip to the roll, and the housing 32 thereof is provided at one end with a hub 59 which fits closely against the end of the roll. At 95 its opposite end the housing is closed by a movable head 60 having an annular marginal flange 61 fitting within the end of the housing. The hub 60 has a central opening for receiving the roll, and the adjacent 100 end of the roll is provided with a tapering depression 62, for receiving a similarly shaped projection 63 on a disk 64 arranged in a casing 65 of cylindrical shape secured to the adjacent cheek plate 5 by means of 105 rivets 66 or the like.

The casing 65 is arranged at that end of the roll adjacent to the crank arm 47, and the inner end of the said casing is provided with a hub 67 fitting within an opening in 110 the cheek plate 5, and receiving the adjacent end of the roll 31. The outer end of the casing 65 is closed by a head or cap 68 having spaced inwardly extending lugs 69 fitting within the casing 65, and screws 70 are 115 passed through the casing 65 and the lugs, to hold the cap 68 in place. The head 68 has a central opening, and the shank or barrel 71 of a winding key passes through the opening, and engages a depression 72 in the 120 outer face of the disk 64. The winding key comprises the shank or barrel 71, and a head 73 arranged transversely of the shank, for convenience in turning the same, and a coil or helical spring 74 is arranged in the casing 65 adjacent to the disk 64.

The inner end of the spring 74 is received in a transverse slot 75 in the barrel or shank of the key, and the outer end of the spring is provided with a bearing 76 in 13

which is received a pin 77 extending laterally from the disk 64 near its periphery. A ratchet wheel 78 is secured to the barrel or shank 71 of the key adjacent to the head 68, and a pawl 79 is pivoted to the head 68 and coöperates with the ratchet wheel, to prevent reverse movement of the key. The pawl is normally pressed into contact with the ratchet wheel by means of a spring 80, the said spring being supported by a pin 81 on the head 68. The disk 64 is provided on its periphery with an annular series of openings 82, and a catch 83 is hinged to the outer surface of the casing 65, as indicated at 84, for coöperating with the opening 82, to hold the disk from movement. The catch extends through an opening in the casing 65, into engagement with the opening 82. A finger piece 85 is provided for operating the catch, and a disk or washer 86 is arranged between the spring 74 and the ratchet wheel 78, the said disk or washer having an opening for the shank or barrel of the key. The projection 63 is polygonal in cross section, and engages a similarly shaped opening in the end of the roll 31, to constrain the roll to rotate with the disk.

Guide plates 87 and 88 are arranged transversely of the cheek plates 5 between the rolls 14 and 31, the said plates being spaced apart from each other and being curved or arched transversely, and arranged with their convex faces adjacent. The said plates guide the strip 19 as it leaves the cutting device, and a guard 89 is arranged in front of the strip 18. The said guide or guard plates 87, 88 and 89 guide the strips 18 and 19 rearwardly away from the operator, as shown in Figs. 1 and 3, in order that they may be readily removed after the strips have been separated into sheets.

In operation, the strips of paper 18 and 19 and the strip of carbon 30 are drawn downwardly over the guard plate 36—37, and beneath the platen roll, in superposed relation, the sheet 18 being outermost. The typewriter is operated in the usual manner, and for each line the platen roll is turned to advance the strips. As the strips 18 and 19 are written upon, they are turned upwardly, the latter passing between the guard plates 88 and 87, and the former between the guard plate 89 and the housing 32 of the carbon receiving roll. The strips are divided into sheets of suitable length by the cutting device, which may be operated at will, by merely depressing the finger piece of the crank arm 47. Before commencing operations, the outer end of the carbon strip should after it has been passed beneath the platen roll be connected with the spurs or lugs 58 on the carbon receiving roll. After this connection has been made, the spring 74 should be wound up, by means of the key 71—73. Before commencing writing, the

catch 83 is released from the disk 64. When now the platen roll is turned to advance the strips 18—19—30, the spring 74 will rotate the roll 31 to take up the carbon strip and to retain the said strip in a taut condition between the rolls 15 and 31.

By means of the nuts 41^a, the cutting device may be adjusted vertically. To adjust said device, the nuts 41^a are loosened, and the frame constituted by the plates 40 and the cross bars 41 may be raised or lowered, the threaded stems 40^a moving in the slots 46^a and the shaft 45 moving in the slots 46. The platen roll is operated by the usual knob or head 90 and the carbon receiving roll is provided with a head or knob 91 at the opposite end from the knobs or heads 16 and 17. The lugs 11 before mentioned engage above and below the end members of the typewriter carriage, and the said lugs 85 are on the lower ends of arms 92 which are secured to the cheek plates 5, by means of screws 93 or the like. The said screws are passed from without inward, and the bearing arms 7 are connected with the cheek 90 plates by screws 94.

It will be evident that the sheets severed from the strips by the cutting mechanism may be of any desired size, as for instance, letter head size, and the strips may be provided with printed matter if desired in the same manner as letter heads, the sections of the printed matter being spaced at proper intervals to make letter sheet size sheets when cut between the sections of printed matter. If desired, lines or any suitable form of guide may be arranged transversely of the strips 18—19 at spaced intervals, to indicate the line of separation.

When the receiving carbon roll 31 is full, it is interchanged with the roll 15. That is when the carbon has been exhausted, or nearly so, from the roll at 15, and has been wound upon the roll at 31, the remainder of the strip is wound upon the roll 31, and the rolls are interchanged after which the carbon strip is threaded around the platen roll, and made fast to the teeth of the spurs on the roll 31. The rolls 15 and 31 are similar, in order that the interchange may be made. The cutting blades are held firmly on the shear bars, by means of holding screws 96. The said screws pass through transverse slots 97 in the blades, into engagement with the shear bars, so that the blades may be adjusted transversely with respect to the shear bars.

We claim:—

1. The combination with the carriage and the platen roll of a typewriter, of a supporting frame detachably connected with the carriage, supporting rolls journaled transversely of the frame and adapted to support strips of paper, a carbon strip supporting roll arranged between the first-named rolls, 130

said strips being adapted to pass beneath the platen roll in superposed relation, a receiving roll for the carbon strip, spring mechanism acting normally to turn the said receiving roll to wind up the carbon strip, a releasable catch for holding the said mechanism in inoperative position, a housing for each of the said rolls, and cutting mechanism for the paper strip between the carbon strip receiving roll and the platen roll and supported by the frame.

2. The combination with the typewriter having a platen roll, of a plurality of rolls for supporting strips of paper arranged adjacent to the platen roll and in rear of the same, a second roll arranged between the first-named rolls for supporting a strip of carbon, a receiving roll at the front of the platen roll and above the same for receiving the carbon strip, a guide in rear of the platen roll and in front of the delivery rolls for the paper and carbon strips over which the said strips pass from the rolls to the platen roll, said guide superposing the paper strips upon each other with the carbon strip between the same, and a cutting device for each paper strip, said cutting devices being at the front of the platen roll and above the same and between the same and the receiving roll for the carbon strip, each of the said devices comprising a fixed blade on one side of the strip and a movable blade on the other side of the strip for coöperating with the fixed blade to sever the strip.

3. The combination with the typewriter having a platen roll, of a plurality of rolls for supporting strips of paper arranged adjacent to the platen roll and in rear of the same, a second roll arranged above the platen roll for supporting a strip of carbon, said last-named roll being between the first-named rolls, a receiving roll at the front of the platen roll and above the same for receiving the carbon strip, a guide in rear of the platen roll and in front of the delivery rolls for the paper and carbon strips over which the said strips pass from the rolls to the platen roll, said guide superposing the paper strips upon each other with the carbon strip between the same, and a cutting device for each paper strip, said cutting devices being at the front of the platen roll and above the same and between the same and the receiving roll for the carbon strip.

4. The combination with the typewriter having a platen roll, of a plurality of rolls for supporting strips of paper arranged adjacent to the platen roll and in rear of the same, a second roll arranged above the platen roll for supporting a strip of carbon, said last-named roll being between the first-named rolls, a receiving roll at the front of the platen roll and above the same for receiving the carbon strip, a cutting device for each paper strip, said devices being at

the front and above the platen roll, and means for simultaneously operating the cutting devices.

5. The combination with the typewriter having a platen roll, of a plurality of supporting rolls for supporting paper strips in rear of the platen roll, a plurality of supporting rolls for the carbon strip, one of the said rolls being in rear and the other at the front of the platen roll, the rolls for the paper strips being on opposite sides of the carbon strip as the said strips pass from their respective rolls under the platen roll, and means in front of the platen roll for cutting each of the paper strips.

6. In a typewriter appliance, a frame for connection with the carriage of a typewriter, a plurality of paper strip supporting rolls journaled in the frame, a carbon strip supporting roll journaled transversely of the frame between the first-named roll, a spring actuated carbon receiving roll at the front of the frame, and cutting mechanism below the said carbon receiving roll for cutting the paper strips, said mechanism comprising an auxiliary frame adjustable vertically of the main frame, fixed blades arranged transversely of the auxiliary frame, movable blades for coöperating with the fixed blades, a carriage to which the said movable blades are secured, springs normally holding the carriage with the movable blades in spaced relation to the fixed blades to permit the passage of the strips, and means for moving the carriage against the resistance of the springs.

7. The combination with the typewriter having a platen roll, of a plurality of supporting rolls for supporting paper strips in rear of the platen roll, a plurality of supporting rolls for a carbon strip, one of the said rolls being in rear and the other at the front of the platen roll, the rolls for the paper strips being on opposite sides of the carbon strip as the said strips pass from their respective rolls under the platen roll, and spring mechanism in connection with the carbon strip supporting roll at the front of the platen roll for winding the carbon strip as it leaves the platen roll, winding means for the spring mechanism, and releasable means holding the spring mechanism in inoperative position.

8. The combination with the typewriter having a platen roll, of a plurality of supporting rolls for supporting paper strips in rear of the platen roll, a plurality of supporting rolls for a carbon strip, one of the said rolls being in rear and the other at the front of the platen roll, the rolls for the paper strips being on opposite sides of the carbon strip as the said strips pass from their respective rolls under the platen roll, and a spring mechanism in connection with the carbon strip supporting roll at the front

of the platen roll for winding the carbon strip as it leaves the platen roll.

9. The combination with the typewriter having a platen roll, of a plurality of rolls for supporting strips of paper arranged adjacent to the platen roll and in rear of the same, a second roll arranged between the first-named rolls for supporting a strip of carbon, a receiving roll at the front of the platen roll and above the same for receiving the carbon strip, a guide in rear of the platen roll and in front of the delivery rolls for the paper and carbon strips over which the said strips pass from the rolls to the platen

rolls for superposing the strips upon each other with the carbon strip between the same, and a cutting device for simultaneously severing the paper strips, said device being arranged between the platen roll, and the receiving rolls for the paper and carbon strips.
